DOUBLE DOOR CLOSET

Harry Derman, Laurelton, Long Island, N. Y.

Application January 15, 1938, Serial No. 185,144

9 Claims. (Cl. 312—190)

This invention relates to closets preferably of the collapsible or knock-down type, and more particularly to closets constructed of corrugated or card-board in the back, sides and top and bottom walls, and utilizing a wood frame at the front of the closet forming a door opening; and the object of the invention is to provide a closet of the character described with means at the upper and lower portions of the door frame and disposed within the cabinet for supporting spring rollers in connection with the frame to constitute a unit part thereof upon which flexible door or closure members, such for example as single-faced corrugated sheets are rolled when the separate door members are in open position; a further object being to provide the free edges of the doors with finishing strips which are adapted to be brought together and to interlock when the doors are moved into closed position, with means for coupling said strips to retain the doors against opening movement; a further object being to provide means for coupling the strip of one door with the strip of the opposed door so that manual movement of one door will be transmitted to the other door, especially in the operation of moving the doors into closed position, and further to the provision of a coupling means which will permit the movement of one door at a speed greater than the other door so that one door will occupy a greater area of the door opening than the other of said doors when both doors are in closed position; and with these and other objects in view the invention consists of a device of the class and for the purpose specified which is simple in construction, efficient in use, and which is constructed as hereinafter described and claimed.

The invention is fully disclosed in the following specification, of which the accompanying drawings forms a part, in which the separate parts of my invention are designated by suitable reference characters, and in which:

Fig. 1 is a vertical sectional view through a cabinet made according to my invention with parts of the construction broken away in order to show certain of the parts on an enlarged scale.

Fig. 2 is a partial section on the line 2—2 of Fig. 1 and also showing the parts of the construction broken away.

Fig. 3 is a partial section on the line 3—3 of Fig. 2 with parts of the construction broken away.

Fig. 4 is a view similar to Fig. 1 showing only a part of the construction and showing a modification, and

Fig. 5 is a perspective view of a cabinet showing another form of construction which I employ.

Insofar as the general structure of the closet or cabinet is concerned, that is to say apart from the structural features of the door frame and its associated parts, it is the same as that disclosed in my application, Serial No. 173,356 filed November 8, 1937, and consists of one part 10 of corrugated or other paper board folded to form a back wall 11 and side walls 12. Top and bottom wall parts 13 and 14 are also employed, these parts having flanges 13a, 14a which extend onto the walls 11 and 12 and are secured thereto by suitable fastener devices to form an elongated cabinet which is open at the front.

At the front of the cabinet is a door frame unit 15 which as a unit is detachable with respect to the remainder of the assembled closet. This frame consists of wooden side rails 16 and top and bottom rails 17 and 18. The side rails have 20 grooves 19 on their opposed surfaces, which grooves open into admission passages 20 at the top and bottom of the frame. In the passages are supported guide rollers 21 for guiding top and bottom door members 22, 22a in their movement 28 into and out of the grooves 19 and also onto top and bottom spring rollers 23, 23a.

It will be understood that one end of the flexible door members 22, 22a is attached to the respective rollers 23, 23a, and the other free ends thereof are attached to reinforcing and guide strips 24, 25 which are provided at their ends with tongues 24a, 25a which operate in the grooves 19 as the strips 24 and 25 are moved vertically in the door frame. Adjacent surfaces of the strips 24 35 and 25 are of irregular contour as seen at 26 so as to interlock or overlap when the strips are brought together so as to render the cabinet as near dustproof as possible.

Supported on the inner surface of the strip 25 40 is a spring catch device 27 having an aperture 28 therein which is adapted to engage a fixed coupling pin 29 forming part of a plate 30 secured to the inner surface of the strip 24. Passed through the plate 30 and the strip 24 is a push-pin 31, the inner end of which is adapted to engage the spring catch 27 to release the same from the pin 29 in the operation of uncoupling the door members to permit automatic movement thereof into open position by the spring rollers 30 23, 23a.

It will be understood that any type of flexible construction may be employed in the door members 22, 22a, and in the construction shown, these door members are composed of what is known as 35

single-faced corrugated board with the corrugations arranged on the outer surface of the sheet. Supported on the inner surface of the door frame 15 at the upper and lower corner portions 5 thereof are inwardly projecting brackets 32 having laterally pressed domes 33 adjacent their inner ends which are apertured as seen for example at 34 in Fig. 1 to receive the projecting shanks of the spring rollers.

10 In this connection it will be understood that while the spring rollers may be of conventional construction it is preferred in the present illustration to remove the usual pawls employed for retarding the progress of the rollers so that when 15 the door members 22, 22a are released the same will automatically move into open position, and the tension of the rollers will be so adjusted as to provide proper operation of the doors. It is preferred that suitable stops 35 be provided on the 20 rails 16 to stop the opening movement of the door members and so as to leave the door members in a partially closed position to shield as much as possible the spring rollers with the material of the door members wound thereon.

25 The strip 24 is provided with laterally extending metallic straps 36, the ends of which are set inwardly and project beyond the side edges of the strip 24. Similar straps 36a are attached to the rail 25. Small pulleys 37 are also supported 30 upon the inner surfaces of the upper brackets 32. I also employ two cords, wires or flexible strands 38, one end 38a of each of which is attached to the straps 36, the strand 38 passing upwardly and around the pulleys 37 and then downwardly, and 35 the other ends 38b thereof are attached to the straps 36a.

It will thus be seen that in manually moving the strip 24 downwardly, the strip 25 through the flexible strands 38 is moved upwardly. In both 40 cases, the door members 22, 22a are unwound from the spring rollers against the tension of the springs thereof. When the strips 24 and 25 abut, the spring catch 27, by virtue of the curved structure thereof, note Fig. 1, will automatically 45 engage the pin 29 and the strips 24 and 25 will be coupled together. By pushing the release pin 31 inwardly, the strips 24 and 25 will be uncoupled and the spring rollers 23, 23a will automatically wind the door members 22, 22a. In this operation 50 the strands 38 act as a balancing means controlling the relative movement of the strips 24, 25 so that said strips will move collectively.

It will appear from a consideration of Figs. 2 and 3 of the drawings that the brackets are arranged in abutting relation to the side walls 12 of the closet. This gives added rigidity to the entire closet structure as well as serving to brace the brackets within the cabinet. In this connection it will also appear that the upper edges of 60 the upper brackets are arranged adjacent the inner surface of the top wall 13, and the lower edges of the lower brackets engage the inner surface of the bottom wall 14. Each bracket 32 is of the same general construction aside from the fact 65 that they may be made lefts and rights and also aside from the particular form of the apertures 34 employed therein for receiving the shanks of the spring rollers.

As previously stated, the door frame and its 70 associated parts constitute the unit 15, which as such, is attachable and detachable with respect to the remainder of the cabinet. In shipment, the collapsed back and side walls are arranged upon one surface of this unit with the top and bottom 75 walls preferably between the top and bottom

brackets. At 39 I have shown a conventional garment hanger which is employed when the closet is used as a wardrobe for the storage of various kinds of apparel. The structure of this hanger is clearly shown in the application herein before 5 referred to.

In Fig. 4 of the drawings I have shown a slight modification of the structure shown in Figs. 1 to 3. In these figures 40, 40a represent door members substantially the same as the door members 10 22, 22a with the exception that the door member 40 is shorter than the door member 40a and will cover, for example, one third of the door opening of the frame unit 15, whereas the door member 40a will cover two-thirds of the door opening. 15 One method of accomplishing this result is to provide strands 41 similar to the strands 38, but instead of coupling the same in the manner shown in Fig. 1, one end 41a of the strands 41 is attached to the upper part of the frame and then 20 passes downwardly and around the pulleys 42 attached to the inner surface of a strip 43 on the door 40, then downwardly and around pulleys 44 similar to the pulleys 37, and then downwardly, attached as seen at 41b to the strip 45 at the free 25 edge of the door 40a.

In other words, with this construction the door 40a together with the strip 45 will move twice as far as the door 40 and strip 43, but otherwise the construction and operation of the device shown 20 in Fig. 4 will be the same as that shown in the other figures. All other parts than those specifically mentioned in connection with Fig. 4 will be the same as the structure shown in the other figures, therefore no specific mention will be made 35 thereof. It will be understood, however, that the tension of the rollers controlling the doors 40, 40a will be regulated to control the particular door operation which is provided in Fig. 4.

It will be understood that any type or kind of 40 differential action may be provided between the door members of the cabinet. In Fig. 5 of the drawings I have illustrated diagrammatically another adaptation of the structure shown in Fig. 4. In this construction the cabinet 10a has a door 45 frame unit 15a which differs from the unit shown in Figs. 1 to 4 inclusive primarily in the provision of a transverse subdividing section 46 having a top rail 47, a bottom rail 48 and a narrow front wall portion 49 preferably of corrugated board to 50 match the upper and lower doors 50, 50a. These doors have at their free edges strips 51, 52 similar to the strips 43, 45 but which register with the strips 47, 48 respectively rather than with each other. With this construction a catch or 55 coupling device as shown in Figs. 1 and 2 will be arranged between the parts 47 and 51 and will be released by a pin 31a similar to the pin 31.

The only difference in the structure shown in Fig. 5 of the drawings resides in the fact that the door 50 will move at a greater distance than the door 50a which is simply a reversal of the structure shown in Fig. 4. The cabinet shown in Fig. 5 may be used as a combination short garment support having at its lower end a shoe or other 60 compartment, or the same may be used for various kinds and classes of storage compartments. While I have shown the doors as coupled together for synchronized or joint operation, it will be apparent that by providing independent catch devices for each door, the couplings between the doors will be eliminated.

It will be understood that one of the advantages of the construction shown in Figs. 1 to 4 inclusive is to provide a great as possible door 75

opening to avoid the necessity of unnecessary stooping on the part of the operator in moving the door or doors into closed position. With the construction shown in Figs. 1 and 2, the two doors meet at what might be termed a midway position, whereas with the structure shown in Fig. 4, the doors meet at a position near the top of the cabinet so that the same may be operated both in closing and opening the door without the necessity of the operator stooping or bending in any way. This latter construction is especially practical in the operation of removing garments from the closet and then performing the operation of closing the door.

15 It will be understood that by constructing the door frame and its associated parts including the brackets, rollers, door members, and so forth, in the form of the unit which is assembled at the factory, and especially in assembled condition, the purchaser experiences little or no difficulty in assembling the complete cabinet. The bottom wall 14 is first placed on the floor and the back and side walls 11 and 12 are then attached to the flanges of the bottom wall after which the garment hanger 39 is placed in position to support the upper edges of the side walls in spaced relation. The unit 15 is then placed in position and attached to the bottom wall and forward edges of the side walls in the usual manner and as indicated in Fig. 3, after which the top wall 13 is placed in position and secured to the walls 11 and 12 and the top rail 17 of the unit 15. The several securing devices are not shown since these are commonly known in this art. When the parts are assembled as above stated, it will appear that the cabinet or closet is ready for use.

Having fully described my invention, what I claim as new and desire to secure by Letters

40 Patent, is:

1. A collapsible closet of the character described, comprising back, side and top and bottom walls, a front door frame unit coupled with the side and top and bottom walls and forming a door opening in the closet, two flexible door members, means at the upper and lower portions of said unit and on the inner surface thereof for supporting the door members in rolled condition, reinforcing and finishing strips at the free edges of the door members mounted and movably guided in the door frame to guide the door members in their movement in said frame to open and close said door opening, said door members being manually movable into closed position against the action of said first named means, and means for retaining the door members in closed position.

2. A collapsible closet of the character described, comprising back, side and top and bottom walls, a front door frame unit coupled with the side and top and bottom walls and forming a door opening in the closet, two flexible door members, means at the upper and lower portions of said unit and on the inner surface thereof for supporting the door members in rolled condition, reinforcing and finishing strips at the free edges of the door members mounted and movably guided in the door frame to guide the door members in their movement in said frame to open and close said door opening, said door members being manually movable into closed position against the action of said first named means, means for retaining the door members in closed position, means arranged longitudinally of the frame and constituting a unit part thereof coupling said

door members together whereby the manual movement of one door member will operate the other of said door members, and said last named means including means whereby one of said door members will move a greater distance than the other of said door members in moving both door members into closed position.

3. In a cabinet of the class described, a door and door frame unit comprising an oblong rectangular frame, a pair of brackets supported in connection with one end of the frame at one side thereof, another pair of brackets on the same side of the frame and at the other end thereof, a spring roller mounted in each pair of brackets, side rails of said rectangular frame having longitudinal grooves on the inner opposed surfaces thereof, said grooves opening through the first named side of the frame adjacent each end, two flexible door members, one of said door members having one end attached to one spring roller and the other having one end attached to the other of said spring rollers, a finishing strip on the free end of each of said door members, said finishing strips and the side edges of the door members being movable in the grooves of the side rails of said frame, said strips being moved into abutting relationship with each other in moving the door members into closed position against the action of said spring rollers, and interengaging couplings on said strips for retaining the door members in closed position.

4. In a cabinet of the class described, a door and door frame unit comprising an oblong rectangular frame, a pair of brackets supported in connection with one end of the frame at one side thereof, another pair of brackets on the same side of the frame and at the other end thereof a spring roller mounted in each pair of brackets, side rails of said rectangular frame having longitudinal grooves on the inner opposed surfaces thereof, said grooves opening through the first named side of the frame adjacent each end, two flexible door members, one of said door members having one end attached to one spring roller and the other having one end attached to the other of said spring rollers, a finishing strip on the free end of each of said door members, said finishing strips and the side edges of the door members being movable in the grooves of the side rails of said frame, said strips being moved into abutting relationship with each other in moving the door members into closed position against the action of said spring rollers, interengaging couplings on said strips for retaining the door members in closed position, means involving strands coupled with the strips of each door member and guided in members supported in said frame whereby the movement of one door member into closed position will move the other of said door members into closed position, and the coupling of the strands with said door members and frame being such as to provide differential movement of the door members one with respect to the other.

5. In a cabinet of the class described, a door and door frame unit comprising an oblong rectangular frame, a pair of brackets supported in connection with one end of the frame at one side thereof, another pair of brackets on the same side of the frame and at the other end thereof a spring roller mounted in each pair of brackets, side rails of said rectangular frame having longitudinal grooves on the inner opposed surfaces thereof, said grooves opening through the first named side of the frame adjacent each

end, two flexible door members, one of said door members having one end attached to one spring roller and the other having one end attached to the other of said spring rollers, a 5 finishing strip on the free end of each of said door members, said finishing strips and the side edges of the door members being movable in the grooves of the side rails of said frame, said strips being moved into abutting relationship with each 10 other in moving the door members into closed position against the action of said spring rollers, interengaging couplings on said strips for retaining the door members in closed position, means involving strands coupled with the strips 15 of each door member and guided in members supported in said frame whereby the movement of one door member into closed position will move the other of said door members into closed position, the coupling of the strands with said 20 door members and frame being such as to provide differential movement of the door members one with respect to the other, means for guiding the door members between the grooves and said spring rollers, and means for limiting the 25 opening movement of said door members.

6. A container of the class described having a front opening, means forming a reinforcing frame bordering said opening, two closure members composed of flexible material supported at 30 opposite end portions of the container adjacent said opening, means for guiding said members in the frame in the movement thereof into open and closed positions, means coupling said members together whereby the movement of one of said 35 members in at least one direction in said frame will move the other of said members in the opposite direction, and said last named means including means whereby one of said members will be moved a greater distance in the frame than the other of said members.

7. In a cabinet of the class described having an opening at one side thereof, a frame bordering said opening, two door members slidably engaging the frame controlling said opening, a spring 40 roller for each door member, said door members being composed of flexible material and normally wound upon said spring rollers, means for mounting one spring roller within the top of the cabinet adjacent said frame, means for mounting the other spring roller in the bottom of the cabinet adjacent said frame, said door members being manually movable into closed position against the action of said spring rollers, means for coupling 45

the door members when moved into closed position and abutting relationship whereby in the release of said last named means the door members will be automatically operated by said spring rollers, other means coupling the door members 5 together whereby the manual operation of one door member against the action of its spring roller will actuate the other door member against the action of its spring roller, and said last named means including means for imparting a greater 10 movement to one of the door members than is attributed to the other of said door members.

8. In a cabinet having an opening in one side thereof, a unitary rectangular frame detachable with respect to the cabinet and bordering said 15 opening, inner opposed surfaces of the side rail of the frame having longitudinal channels, two door members composed of flexible material supported within the cabinet at the ends of said frame, said door members each slidably engaging the channels of the frame to control the opening of said cabinet, spring rollers supporting said door members in roller condition, means retaining the door members in closed position against the action of said spring rollers, means 20 for guiding the flexible doors from the spring rollers into the channels of said frame and means supporting said spring rollers upon inner surfaces of said frame to constitute a unit part thereof.

9. In a cabinet having an opening in one side thereof, a unitary rectangular frame detachable with respect to the cabinet and bordering said opening, inner opposed surfaces of the side rails of the frame having longitudinal channels, two 35 door members composed of flexible material each slidably engaging the channels of the frame to control the opening of said cabinet, means at the ends of said frame and upon inner surfaces thereof and constituting a unit part of said frame to which one end portion of each door member is secured, whereby said door members constitute a unit part of said frame, reinforcing and finishing strips at the other free edges of the door members mounted and movably guided 40 in the door frame, and means supported on the frame at each side thereof and coupled with both door members, whereby the movement of one of said members in at least one direction in said frame will move the other of said members in the opposite direction in controlling said door opening.

HARRY DERMAN.
